(57) **CLAIM**

The ornamental design for a power adapter, as shown and described.

DESCRIPTION

FIG. 1 is a front perspective view of a power adapter according to a first embodiment of our design;

FIG. 2 is a front elevation view of the power adapter of FIG. 1;

FIG. 3 is a back elevation view of the power adapter of FIG. 1;

FIG. 4 is a right elevation view of the power adapter of FIG. 1;

FIG. 5 is a left elevation view of the power adapter of FIG. 1;

FIG. 6 is a top plan view of the power adapter of FIG. 1; and, FIG. 7 is a bottom plan view of the power adapter of FIG. 1. The broken line showing of a power adapter represents unclaimed subject matter and forms no part of the claimed design.

1 Claim, 2 Drawing Sheets
